DAVID H. WARD, OF SEATTLE, WASHINGTON.

MEANS FOR CUTTING AND REMOVING THE ENDS OF CANS.

1,321,578.

Specification of Letters Patent. Patented Nov. 11, 1919.

Application filed December 19, 1918. Serial No. 267,514.

To all whom it may concern:

Be it known that I, DAVID H. WARD, a citizen of the Dominion of Canada, residing at Seattle, in the county of King and State of Washington, have invented certain new and useful Improvements in Means for Cutting and Removing the Ends of Cans, of which the following is a specification.

This invention relates to a machine for cutting and removing the top and bottom ends of the standard five-gallon oil can.

A demand has been made for a machine that will expeditiously and cleanly remove each end of such a can, cutting the end just within the flange of the end seam. That will effect the cut as close as practicable against the sides of the can that the cut edges will not interfere with the free outpouring and complete removal of the contents.

The machine by which these requirements have been met is fully set forth in the following specification, reference being made to the drawings by which it is accompanied, in which:

Figure 1 is an end elevation of the can clamping and end cutting means, the nearer guide columns on one side being removed, and certain parts shown in section.

Fig. 2 is a sectional plan on the line 2—2 in Fig. 1 showing the clamp in the can holding position.

Fig. 3 is an inverted plan of the cover cutting head.

Fig. 4 is a side elevation of one of the can clamp members.

Fig. 5 is an enlarged detail of the spring clip of the clamp.

In these drawings 2 represents a standard five-gallon oil can, such as the device is designed to cut and remove the ends of. These cans are delivered one at a time by any suitable means to the place of cutting, along a slide-way 3 of angle iron, and are sustained by such slideway during the clamping and cutting operation.

At the place of cutting these angle irons 3 are supported between vertically disposed angle iron columns 4, which carry also the can clamping means, and form guide-ways

for the cutter head.

Each can as delivered to the place of cutting, comes to rest between opposed clamp members 5 which are pivotally mounted one

on each side of and parallel to the slideway 3, each on a pin 6 secured adjacent the level 55 of the slideway track 3, between a pair of the columns 4. In shape the clamps turn inward from their pivot pins 6 toward the slideway 3 and upward to bear against each opposite side of the can, and have flanges 7 to engage 60 the adjacent corners of the can when clamped.

These clamp members 5 are normally maintained clear of the sides of a can on the slide-way track 3 by springs 8. Adjacent each 65 corner the back of each clamp is shaped, as at 10, to be engaged and forcibly moved into the clamping contact with a can on the slideway by roller wheels 9 which are rotatably mounted in the lower ends of members 11 downwardly projecting from each corner of a head 12 which is vertically slideable within the group of columns 4, the upper and lower ends of each downwardly projecting portion 11 being shaped, as at 70 75 17, to engage the inner corner of each column.

Secured to the underside of the central portion of the head 12 is an open knife-holding frame 13 to the inner sides of which 80 are secured the knife blades 14, the four blades conforming in plan to the inner square of the end flange of the can. The cutting edge of each blade is angled downward to its middle from each end, forming approximately ninety degrees, and is beveled 85 from the outer to the inner side of the blade, so that when the cutter head is forced down the angular point of each blade will penetrate the can end and the cut is effected from the middle of each side outward to each corner.

As the flanges of the can ends are occasionally battered or bent inward, the extreme angular point of each blade is bent 95 inward, as at 15, toward the center of the square of the can, to insure that it will penetrate the can end and will not engage an inwardly bent flange, and as the knives penetrate, the cut gradually approaches the 100 true line of the inner side of the flange, the bevel and rigidity of the blades rectifying the edges of the flange.

The end cover of the can is thus cut close along the edge of the flange to each extreme 105 corner, and the cut cover is retained within

the knife blade frame 13 and is removable through a lateral aperture 16 between the knife frame and the head 12.

Suitable mechanism is provided for periodically reciprocating the head 12 with its clamping rollers and can cutting knife blades through a downward movement to clamp the can and effect the cutting of the cover and thereafter to withdraw the knives and release the clamp. This may be effectively done by a crank and connecting rod.

To hold the can during the withdrawal of the knives 14, which withdrawal also effects release of the clamp, a spring clip 22 is secured to the middle of each clamp 5 to project over the upper edge of the can and is turned upward and backward, as shown, that it will be engaged and pressed back clear of the knife blade as it descends. The inner edge of this clip is withdrawn with the clamp clear of the can when the clamp is fully released.

The removed ends of the cans cut are retained within the square of the knife blades, and as they accumulate are pushed upward and may be withdrawn through the lateral aperture 16 provided in the knife holding frame.

The ends being cleanly removed leaves the can in a favorable condition for the further treatment of removing the other end and flattening the body portion of the can across one diagonal for shipment as a "return empty."

Having now particularly described my invention, I hereby declare that what I claim as new and desire to be protected in by Letters Patent, is:

1. A means for cutting and removing the end cover of a can, said means comprising a knife conforming in plan to the size and shape of the can end within the end seam, the cutting edge of the knife being angularly pointed at diametrically opposite sides and the outer end of each point turned inward so as to penetrate the cover slightly within the general line of the end seam and means for moving the cutting knife endwise in the axial line of the can.

2. A means for cutting and removing the end cover of a can, said means including a knife conforming in plan to the size and shape of the can end within the end seam, the said knife consisting of a set of V-shaped cutting members, the cutting edges of which being beveled on the outer side and the points being angularly pointed inwardly so as to penetrate the cover slightly within the general line of the end seam, and means for moving the cutting knife endwise in the axial line of the can.

3. A means for cutting and removing the end cover of a can, said means comprising a knife conforming in plan to the size and

shape of the can end within the end seam, 65 the cutting edge of the knife being angularly pointed at diametrically opposite sides and the outer end of each point turned inward so as to penetrate the cover slightly within the general line of the end seam, 70 means for moving the cutting knife endwise in the axial line of the can, a track along which the can is delivered to the place of cutting and by which it is supported thereat, and means for holding the can down on the 75 supporting track.

4. A means for cutting and removing the end cover of a can, said means comprising a knife conforming in plan to the size and shape of the can end within the end seam, 80 the cutting edge of the knife being angularly pointed at diametrically opposite sides and the outer end of each point turned inward so as to penetrate the cover slightly within the general line of the end seam, 85 means for moving the cutting knife endwise in the axial line of the can, and means for clamping the can with its axis corresponding substantially with that of the movement of the cutting knife.

5. A means for cutting and removing the end cover of a can, said means comprising a knife conforming in plan to the size and shape of the can end within the end seam, the cutting edge of the knife being angularly pointed at diametrically opposite sides and the outer end of each point turned inward so as to penetrate the cover slightly within the general line of the end seam, means for moving the cutting knife endwise in the 100 axial line of the can, a clamp device co-operative with the movement of the knife to clamp the can during the cutting movement and release it during the withdrawal movement of the knife.

6. A means for cutting and removing the end cover of a can, said means comprising a knife conforming in plan to the size and shape of the can end within the end seam, a vertically movable head to which said 110 knife is secured, a track along which the cans are delivered to and from the place of cutting and on which they are supported thereat, a clamp member pivotally mounted at each side of the track at the place of cutting, means for normally holding the clamp members clear of a can on the track, and means on the knife head for moving the clamp members to secure the can as the knife head descends.

7. A means for cutting and removing the end cover of a can, said means comprising a knife conforming in plan to the size and shape of the can end within the end seam, a vertically movable head to which said 115 knife is secured, a track along which the cans are delivered to and from the place of cutting and on which they are supported

thereat, a clamp member pivotally mounted at each side of the track at the place of cutting, means for normally holding the clamp members clear of a can on the track, and 5 means on the knife head for moving the clamp members to secure the can as the knife head descends, each of said clamping members

having means for engaging the upper edge of the can and holding it down on its support as the knife head is withdrawn and the clamp released.

In testimony whereof I affix my signature.

DAVID H. WARD.
